UNITED STATES PATENT OFFICE.

CURNEALUS HOOK, OF VIGO, OHIO.

KILN.

1,073,045.

Specification of Letters Patent.

Patented Sept. 9, 1913.

Application filed July 2, 1912. Serial No. 707,309.

To all whom it may concern:

Be it known that I, CURNEALUS HOOK, a citizen of the United States, residing at Vigo, in the county of Ross and State of 5 Ohio, have invented new and useful Improvements in Kilns, of which the following is a specification.

This invention relates to kilns for burning clay products, and it has for its object to 10 produce a kiln of simple and improved construction wherein the up and down draft types of kiln shall be combined in a single structure.

A further object of the invention is to so 15 construct the improved kiln that a combined up and down draft may be produced therein when desired.

With these and other ends in view which 20 will readily appear as the nature of the invention is better understood, the same consists in the improved construction and combination of parts which will be hereinafter fully described and particularly pointed out in the claims.

25 In the accompanying drawings has been illustrated a simple and preferred form of the invention, it being, however, understood that no limitation is necessarily made to the precise structural details therein exhibited, 30 but that changes, alterations and modifications within the scope of the claims may be resorted to when desired.

In the drawings,—Figure 1 is a horizontal 35 sectional view of a kiln constructed in accordance with the invention, said section being taken on the plane indicated by the line 1—1 in Fig. 2. Fig. 2 is a vertical sectional view taken on the line 2—2 in Fig. 1. Fig. 3 is a detail view in elevation of a portion of 40 a kiln showing one of the double furnace archways. Fig. 4 is a horizontal sectional view showing the principles of the invention applied to a rectangular kiln. Fig. 5 is a transverse sectional view taken on the line 45 5—5 in Fig. 4. Fig. 6 is a transverse sectional view taken on the line 6—6 in Fig. 4.

Corresponding parts in the several figures are denoted by like characters of reference.

In the embodiment of the invention shown 50 in Figs. 1 and 2 a circular kiln wall 1 is provided, and double furnace archways 2 are suitably positioned within said kiln wall, as indicated in dotted lines in Fig. 1, said furnace archways being situated below the 55 floor level of the kiln. Each furnace of the

double archways 2 is directly connected with a set of two heat leaders 3, 3 and 4, 4, as shown, one set of leaders 3, 3 being connected with one furnace, and another set of leaders 4, 4 being connected with the other 60 furnace of a double archway 2, a specimen of which is shown in elevation in Fig. 3 of the drawings. These heat leaders are directly below the floor of the kiln, as shown in Fig. 2; those of each set being separated, 65 one from the other, by solid walls 5 and 6 extending parallel and between said heat leaders, and by a solid wall 7 positioned at right angles to the walls 5 and 6 and extending diametrically across the entire under-floor 70 construction.

The heat leaders 3 extend straight from the inside edge of their respective archways for a certain distance within the under-floor construction, and thence in a curved direction for the remainder of their length, while the heat leaders 4 extend in a straight line for their entire length, as shown, and are parallel to the straight part of the heat leaders 3. 75

Sets of heat leaders 3 and 4 corresponding to each double archway 2 and at each side of the diametrical wall 7 are separated one from the other by a solid wall 8 extending from the inside face of the kiln wall 1 to a 80 suitable distance within the under-floor construction, as shown. Branching from near the inner end of each wall 8 and extending for a certain distance parallel to the curved heat leaders 3, a short solid wall 9 is provided for the purpose of diverting the heated air and products of combustion into the curved channel of one heat leader of 85 each set 3. 90

Between sets of heat leaders 3 and 4, and 95 between the heat leaders 3 and the wall of the kiln, a suitable number of solid walls 10, 11 and 12 are provided, all parallel and spaced apart from each other and from the solid wall 7, with their ends terminating at 100 a suitable distance from the walls 5 and 6, thereby coöoperating with said walls to form the said heat leaders.

The entire under-floor construction is pref- 105 erably constructed of brick to the same height upon a base 21, best seen in Fig. 2, the area of which is coextensive with the bottom of the kiln. It will be obvious that the walls 5, 6, 7, 10, 11 and 12, together with the floor, serve the purpose of distributing 110

the heated air and products of combustion over the entire area to be heated.

As will be best seen by reference to Fig. 1, the floor is constructed of brick which, as seen at 15, is laid solid over the heat leaders, while the bricks laid over the remainder of the area to be covered, as seen at 14, are laid across the spaces between the walls 10, 11 and 12 endwise abutting, but spaced laterally to form cracks or openings 14' for the passage of heated air and products of combustion.

Furnace arches 16 are located in the kiln wall at suitable intervals and above the kiln floor, said arches communicating at their inner ends with vertical heat leaders 20, which latter terminate below the spring line of the crown 30 of the kiln. It will be understood that the number of furnaces 2 and 16, as well as that of the walls 10, 11 and 12 will vary with the size of the kiln and that the walls may be arranged in various ways different from that herein shown, without departing from the spirit of the invention.

Stacks 17 are located at suitable intervals either within or without the kiln wall, and each of said stacks is in communication with the interior of the kiln through two archways 18 and 19, see Fig. 2, situated the one above the other and both above the floor, as shown in Fig. 2.

It will be seen that of the two series of furnaces employed, one series comprising the double archways 2 discharges its heat and products of combustion into the heat leaders 3 and 4 situated directly below the floor, while the other series of furnaces 16 discharges its heat and products of combustion into the vertical heat leaders 20 which extend to a suitable height above the floor of the kiln. In Figs. 4, 5 and 6 the application of the invention has been shown to kilns of either square or rectangular shape. The solid walls 22, the heat leaders 23 and 24, the furnace archways 25 and 26, the stacks 27, stack archways 28 and 29 and the solid walls 37 and 38 serve, respectively, the same purpose as do the walls 10, 11 and 12, heat leaders 3, 4 and 20, furnace archways 2 and 16, stacks 17, stack archways 18 and 19, and the solid walls 5, 6 and 7 of the circular kiln.

The stacks 27 are located at suitable intervals either within or without the kiln wall and communicate with the interior of the kiln through two superimposed archways 28 and 29 in precisely the same manner as in the case of the circular kiln. The crown 30 of the kiln in any of the forms herein shown is provided with suitable draft apertures 31 for which closures 32 may be provided, said closures being of such nature that they may be readily removed when desired. Valves or dampers are also

to be provided for the various furnaces and draft apertures.

As previously mentioned, this invention is designed to be a combination of the up and down draft types of kiln. However, it will be seen that in addition to a combination of the up and down draft, either a down draft or an up draft alone may be obtained. The method of bringing about this result will be presently explained.

In the operation of this invention, when both the up and down drafts are desired, the lower archways 19 or 28 are closed by means of dampers 33, and both series of furnaces are fired simultaneously. The heated air and products of combustion from the furnaces located at the archways 2, or 26, are discharged into horizontal heat leaders, 3, 4 or 24 from which, by the arrangement of the floor and walls 10, 11 and 12, or 22, the said heated air and products of combustion are distributed over the spaces between the walls of the under-floor construction, as shown by arrows in Figs. 1 and 4, from whence it passes up through the cracks or spaces left between the floor brick for that purpose, and up through the lower tiers of ware placed on the floor to be burned, and thence to the open air through the stack archways 18 or 29 and stacks 17 or 27, as shown by arrows in Figs. 2 and 5. The heated air and products of combustion from the furnaces located at the archways 16 or 25 will pass directly into and up through the vertical heat leaders 20 or 23 and down through the ware in the usual manner meeting, at or near the level of the stack archways 18 or 29, the heated air and products of combustion rising, as shown by arrows in Figs. 2 and 5, from the under-floor; the heated air and products of combustion from both sources passing out together through the archways 18 or 29 and stacks 17 or 27.

To obtain a down draft alone, it is only necessary to cease firing the series of furnaces 2 or 26, open the stack arches 19 or 28 and obstruct the stack archways 18 or 29. By so doing the heat from the furnaces located at archways 16 or 25 alone is used. It passes up through the vertical heat leaders 20 or 23, down through the ware, and out at archways 19 or 28 and stacks 17 or 27, as shown in Fig. 6.

To secure an up draft, the furnaces located at archways 2 or 26 only are used, and all the stack archways 18 and 19 or 28 and 29 are obstructed. The heated air and products of combustion from said furnaces located at archways 2 or 26 passes into the heat leaders 3 and 4 or 24, and is distributed over the under-floor area, passing from thence up through the floor precisely as in the case of the combined up and down drafts, thence through the ware and out through the apertures 31 from which the

obstructions 32 have been previously removed. When this draft is not desired, the apertures 31 are to be kept tightly closed.

The ware is to be arranged in the kilns 5 in such a manner as to facilitate the above mentioned directions of travel of the heated air and the products of combustion.

A kiln embodying the principles of this 10 invention may be constructed and maintained at a moderate cost, and among the advantages resulting therefrom are the uniformity with which ware can be burned in all parts of the kiln, the small amount of fuel and time required in burning, the ease 15 with which the kiln can be operated, the small amount of excavating necessary, the rapidity with which ware can be "water smoked" without chipping, cracking or "whitewashing" and the rapidity with 20 which the ware can be cooled.

Owing to the improved construction of the kiln a combined up and down draft may be used, the time of burning and consequently the fuel consumption is reduced 25 much below that required by other types of kiln now in use. The ware is uniformly burned in all parts of the kiln on account of the peculiar construction of the under-floor and floor, whereby the heat and products of combustion are evenly distributed 30 over the entire interior of the kiln. It may also be stated that the ware can be cooled rapidly, owing to the fact that the air is enabled to pass up as well as down through 35 the ware by reason of the arrangement of furnaces, heat leaders and stack arches.

Having thus described the invention, what is claimed as new, is:—

1. In a kiln, an outer wall, a floor, furnace arches situated in the wall beneath the floor, a base beneath the floor, solid walls having straight portions built on the base and forming heat leaders arranged in pairs, one pair communicating with and extending 40 from each furnace, and solid walls built on the base intermediate the first mentioned walls and substantially at right angles to the straight portions of said first mentioned walls and coöperating therewith to form 45 heat passages; the floor being supported upon the walls and having solid portions superposed over the heat leaders extending from and communicating with the furnaces, and cracks or apertures communicating with 50 the heat passages diverging from the heat leaders.
2. In a kiln, an outer wall, a floor, furnaces situated in the outer wall below the floor level, heat leaders extending from the 55 furnaces beneath the floor and obstructed

by solid portions of the floor, heat passages diverging from the leader beneath the floor and communicating with the interior of the kiln through apertures in the floor, furnaces situated at intervals in the wall of the 65 kiln above the floor level, vertical heat leaders within the kiln communicating with the last mentioned furnaces, stacks arranged at intervals exterior of the kiln wall, and archways extending through the kiln wall and 70 establishing communication between the interior of the kiln and the stacks.

3. In a kiln, an outer wall, a floor, furnaces situated in the outer wall below the floor level, heat leaders extending from the 75 furnaces beneath the floor and obstructed by solid portions of the floor, heat passages diverging from the leader beneath the floor and communicating with the interior of the kiln through apertures in the floor, furnaces 80 situated at intervals in the wall of the kiln above the floor level, vertical heat leaders within the kiln communicating with the last mentioned furnaces, stacks arranged at intervals exterior of the kiln wall, and archways 85 extending through the kiln wall and establishing communication between the interior of the kiln and the stacks; there being two archways connecting each stack with the interior of the kiln, both of said archways 90 being arranged above the floor level and one superposed above the other.

4. In a kiln, an outer wall, a floor, furnaces situated in the outer wall below the floor level, heat leaders extending from the 95 furnaces beneath the floor and obstructed by solid portions of the floor, heat passages diverging from the leader beneath the floor and communicating with the interior of the kiln through apertures in the floor, furnaces 100 situated at intervals in the wall of the kiln above the floor level, vertical heat leaders within the kiln communicating with the last mentioned furnaces, stacks arranged at intervals exterior of the kiln wall, and archways 105 extending through the kiln wall and establishing communication between the interior of the kiln and the stacks; there being two archways connecting each stack with the interior of the kiln, both of said archways 110 being arranged above the floor level and one superposed above the other; and a crown having apertures and removable closures for the same.

In testimony whereof I affix my signature 115 in presence of two witnesses.

CURNEALUS HOOK.
